(57) **CLAIM**

The ornamental design for a vehicle front side grille, as shown and described.

DESCRIPTION

FIG. 1 is a left side elevational view of a left vehicle front side grille (the right vehicle front side grille being a mirror image and is not shown);

FIG. 2 is a right side elevational view of the vehicle front side grille;

FIG. 3 is a front elevational view of the vehicle front side grille;

FIG. 4 is a top plan view of the vehicle front side grille;

FIG. 5 is a bottom plan view of the vehicle front side grille;

FIG. 6 is a perspective view of the vehicle front side grille; and,

FIG. 7 is another perspective view of the vehicle front side grille.
